ABSTRACT: A clothes hanger adapted to hold trousers, skirts, and the like, preferably molded from a plastic material. An elongate, rigid support bar is provided with a suspension hook adapted to extend from its upper surface intermediate its length so as to hang in horizontal position from a clothes rack. A pair of elongate clamping bars have one set of ends flexibly attached to an end of the support bar for hinge action, and extend along the length of the support bar on opposite lateral sides thereof. Hinge action is achieved by reason of the flexibility of the material forming an outwardly curved portion of the clamping bars at the point of attachment. The opposite ends of the clamping bars and the support bar have latching means for latching the clamping bars in clamping position relative to the support bar so as to hold the men's trousers or other items securely between the clamping bars and the support bar. The clamping bars can have a slight outward bow from approximately midlength to the free ends of the bars for achieving a firmer clamping action on the trousers when the bars are latched to the support bar.

TROUSER AND SKIRT HANGER

BACKGROUND OF THE INVENTION

5

1. Field

This invention relates to clothes hangers, more particularly to hangers for trouser, skirts, and the like.

2. State of the Art

A large variety of clothes hangers is available to the public and include hangers specifically designed for suspending trousers and skirts. The trouser hangers presently available on the market tend to be heavy and difficult to manipulate when inserting the trousers into the hanger. Moreover, many hangers create undesirable wrinkles and creases in the trousers and skirts suspended therefrom.

3. Objective

It was an objective in developing this invention to provide a lightweight, inexpensive and durable hanger, which would be relatively simple to use and would not wrinkle the items of wearing apparel suspended therefrom.

SUMMARY OF THE INVENTION

The hanger of the invention is particularly adapted to hold men's trousers, women's skirts and the like from the cuff or waistband, and is preferably molded from a plastic material, although a combination wood and metal hanger is also contemplated. The hanger has a rigid elongate support bar with a pair of elongate clamping bars extending along the length of the support bar on opposite lateral sides thereof. One set of ends of the clamping bars is flexibly attached to one end of the support bar with the attached end of each clamping bar preferably forming an outwardly curved segment at the point of attachment. The outwardly curved configuration also provides space for the bunching of fabric if necessary, for example, with wide skirts. Sufficient space should be provided between the clamping bars and the support bar to permit items of clothing to be suspended between the bars. Men's trousers are conveniently hung from the cuffs and women's skirts can be suspended from the waistband. The unattached end of each support bar has latching means on either side for holding the two clamping bars in a clamping position relative to the support bar when the ends of the clamping bars are inserted therein. The support bar is provided with a suspension hook disposed along its upper surface intermediate its length for suspending the hanger from a closet rod so that the support and clamping bars are in substantially horizontal position.

In a preferred embodiment, the support bar and two clamping bars are molded as a single unit from plastic material, and the clamping bars have a slight outward bow away from the support bar beginning at approximately the center of the clamping bars and extending to the free ends thereof. This configuration provides a wider space between the free ends of the clamping bars and the support bar for easier insertion of the trousers into the space therefor. The hook is preferably formed as a separate item and locked into position within the support bar, with the open end of the hook facing the end of the support bar which is attached to the clamping bars.

DESCRIPTION OF THE DRAWING

An embodiment of apparatus constituting the best mode presently contemplated of carrying out this invention is shown in the accompanying drawing, in which:

FIG. 1 is a perspective view of the hanger, showing the slight outward bow in the clamping bars with the bars in the open position;

FIG. 2, an end elevation of the hanger showing a pair of trousers suspended from cuffs between one clamping bar and the support bar, with the other bar in the open position;

FIG. 3, a fragmentary longitudinal vertical section taken along the line 3-3 of FIG. 1, showing the detachable hook in elevation mounted in the support bar; and

FIG. 4, a transverse vertical section taken along the line 4-4 of FIG. 1, illustrating the details of the mounted hook.

DETAILED DESCRIPTION OF THE ILLUSTRATED EMBODIMENT

As illustrated in FIG. 1, the plastic embodiment of the hanger 10 has an elongate support bar 11 with a suspension hook 12 attached in the center thereof and extending vertically above the bar 11. A pair of clamping bars 13, 14 extend laterally along the length of the central bar 11 on opposite sides thereof. The two bars 13, 14 are flexibly attached to the support bar 11 at one end 15 of the support bar 11 to form a hinging means for the clamping bars 13, 14. Each clamping bar 13, 14 forms an outwardly curving section 16, 17 at the point of attachment 15 with the support bar 11 to provide storage space for excess fabric of the garment clamped between the bars, e.g., a skirt having a long waistband. The curved portions 16, 17 also provide greater resiliency in the clamping bars 13, 14 and minimize the propensity of the clamping bars 13, 14 to break away from the support bar 11 at the point of attachment 15. This feature permits greater use and longer life for the hanger than would otherwise be possible with a conventional attachment.

At the other end of the support bar 11 a crosspiece 18 having latching receptacles 19, 20 is attached to the support bar 11. The receptacles 19, 20 serve to receive and hold the clamping bars 13, 14 in clamping relation with the support bar 11 when the ends of the clamping bars 13, 14 are inserted therein. It is advantageous for the clamping bars 13, 14 to have small notches 21, 22 located on the lower surfaces of the ends thereof, which serve as guides for the insertion of the ends of the clamping bars 13, 14 into the crosspiece receptacles 19 and 20. Additional features of the preferred embodiment include the longitudinal extension of the ends of the clamping bars 13, 14 beyond the crosspiece receptacles 19, 20, and the beveling of the lateral upper ends 19a, 20a, of the crosspiece 18. The extension of the clamping bars 13, 14 provides convenient means to grasp the bars when inserting them into the receptacles; and the beveled crosspiece ends 19a, 20a permit easy insertion of the bars by simply squeezing the bars laterally toward the support bar so that the bars slide laterally over the beveled edges 19a, 20a.

Between the clamping bars 13, 14 and the support bar 11, sufficient space 23, 24 extending longitudinally along the length of the bars 11, 13, 14, should be provided for inserting items of wearing apparel. The support bars 13, 14 can be placed immediately adjacent the support bar 11 leaving very little space 23, 24 between the clamping bars 13, 14 and the support bar 11 if desired, since the clamping bars are sufficiently resilient to permit some horizontal displacement by nonbulky apparel.

It has been found advantageous to provide the free end of the clamping bars 13, 14 with a slight outward bow away from the support bar 11. The outward bow results in larger spaces 25, 26 near the free ends of the clamping bars 13, 14, serving a dual function. The larger spaces 25, 26 afford easier insertion of the wearing apparel into receptacles 23, 24, and the slight bow at the midpoints 27, 28 of the clamping bars 13, 14 exerts a tighter clamping pressure upon garments located in spaces 23, 24, when the ends of the clamping bars 13, 14 are inserted into the receptacles 19, 20. The outward bow at the midpoints 27, 28 of the plastic clamping bars is more easily retained over a period of continued use if a slightly increased thickness of plastic is used in the clamping bar 13, 14, along its outer lateral sides in the area of the bow 27, 28.

In FIG. 2, the right clamping bar 13 is positioned in the receptacle 19. Trousers are clamped between the clamping bar 13 and the support bar 11 and are suspended by the cuffs thereof to prevent wrinkling. The left clamping bar 14 is in the open position preparatory to receiving an article of wearing apparel. At least two pairs of trousers or other clothing articles can be suspended by the hanger as shown.

The suspension hook 12 need not be an integral part of the support bar 11. As shown in FIGS. 3 and 4, the hook 12 can be formed separately and then attached to the support bar 11 through an aperture 29 in the upper surface of the bar 11. The hook 12 has flanges 30, 31 which support overlying portions 32, 33 of the upper surface of the support bar 11, and thereby support the entire hanger 10. For reduction in weight as well as increased strength, the support bars 13, 14 can be constructed as U-shaped members having hollow interiors 34, 35 and flat upper surfaces. The support bar 11 can also be constructed with a hollow center 36 to facilitate insertion of the hook 12 into position through the aperture 29, as shown in FIG. 4. To prevent accidental removal of the hook 12, the interior walls of the hollow center 36 have flanges 37, 38 which clamp around the bottom of the hook 12, thereby anchoring it in place and providing additional strength to the hanger.

Although the hanger should find its principal use as a support means for trousers or skirts, it is apparent that other items of wearing apparel can be suspended from the hanger provided they can be placed between the clamping bars and the support bar.

The configuration of the clamping bars shown in the accompanying drawings includes a flat upper surface with right-angled sides. The flat upper surface aids in retaining the trousers in the hanger by permitting the cuffs to engage and rest upon the broad upper surfaces of the clamping and central bars as the trousers hang below the hanger.

The outwardly curved portion of the clamping bars which forms the hinging connection with the support bar gives the clamping bars increased resiliency at the primary points of stress. As the clamping bars are opened and closed to receive and release items of wearing apparel, significant stress is applied at the resilient hinge with the support bar. The clamping bars must be capable of repeated opening and closing without losing their resiliency and without cracking or breaking. A right-angled hinging joint would accumulate the major portion of the stress, leading to a high probability of cracking and severing at the joint. By using the semicircular configuration as shown, the stress is distributed more equally throughout the circumference of the semicircle.

The hanger is so designed that the support bar and two clamping bars can be formed or molded as one piece. It is also possible to form the component parts of the hanger as individual pieces and then assemble them into the completed hanger, so long as the clamping bars retain the necessary

resiliency and flexibility to function as described herein. For example, the support bar can be constructed of wood with the clamping bars being made of metal, such as metal wire or the like.

5 1 claim:

1. A clothes hanger, comprising in combination:
a rigid elongate support bar;
a pair of elongate clamping bars extending along the length of said support bar at opposite lateral sides thereof respectively one set of ends of the clamping bars adjacent one end of said support bar forming a resilient attachment at said one end, said resilient attachment having outwardly curved portions with respect to said one end;
latching means at the opposite free ends of said support bar and said clamping bars for latching the clamping bars in clamping position relative to the support bar; and
a suspension hook extending upwardly from said support bar and disposed intermediate the length thereof.

20 2. A clothes hanger as described in claim 1, wherein said latching means comprises a latching crosspiece having notches formed into the upper surface near each end thereof adapted to receive the free ends of the clamping bars.

25 3. A clothes hanger as described in claim 2, wherein the free end of each clamping bar has a notch formed into the lower surface thereof adapted to fit into the corresponding notch in the latching crosspiece.

4. A clothes hanger as described in claim 1, wherein each clamping bar forms an outward lateral bow extending from approximately the midpoint of the clamping bars to the free ends thereof.

30 5. A clothes hanger as described in claim 1, wherein the suspension hook is detachably mounted on the support bar.

6. A clothes hanger as described in claim 1, wherein the suspension hook is positioned with its opening directed toward the attached end of the support bar.

35 7. A clothes hanger as described in claim 1, wherein the hanger is molded of a plastic material.

8. A clothes hanger as described in claim 7, wherein the support and clamping bars are formed as an integral unit.

40 9. A clothes hanger as described in claim 7, wherein the clamping bar and the support bar have a flat upper surface.

10. A clothes hanger as described in claim 1, having the support bar constructed of wood and the clamping bars of flexible metal.
